COMBINED VACUUM TABLE AND FLASH EX- POSURE PANEL FOR USE WITH A DIRECT SCREEN SYSTEM

Marvin Korman, Rego Park, N.Y., assignor to Berkey
Photo, Incorporated, New York, N.Y.

Filed Mar. 13, 1967, Ser. No. 6,175

Term of patent 14 years

(Cl. D33—14)

FIGURE 1 is a front perspective view of a combined vacuum table and flash exposure panel for use with a direct screen system.

FIGURE 2 is a front elevational view.

FIGURE 3 is a side elevational view.

FIGURE 4 is a top plan view; and

FIGURE 5 is a rear elevational view thereof.

I claim:

The ornamental design for a combined vacuum table and flash exposure panel for use with a direct screen system, as shown.
